Primary Examiner — Mitchell I. Siegel

(57) **CLAIM**

The ornamental design for a toy playset, as shown.

DESCRIPTION

FIG. 1 is an exploded front perspective view of the toy playset showing my new design;

FIG. 2 is an exploded rear perspective view thereof;

FIG. 3 is a front perspective view of the toy playset in an assembled condition;

FIG. 4 is a rear perspective view of FIG. 3;

FIG. 5 is a front elevational view of the lower component of the toy playset; shown separately for clarity of illustration;

FIG. 6 is a rear elevational view of FIG. 5;

FIG. 7 is a left side elevational view of FIG. 5;

FIG. 8 is a right side elevational view of FIG. 5;

FIG. 9 is a top plan view of FIG. 5;

FIG. 10 is a rear perspective view of FIG. 5;

FIG. 11 is a front perspective view of FIG. 5;

FIG. 12 is a front elevational view of the upper component of the toy playset; shown separately for clarity of illustration;

FIG. 13 is a rear elevational view of FIG. 12;

FIG. 14 is a left side elevational view of FIG. 12;

FIG. 15 is a right side elevational view of FIG. 12;

FIG. 16 is a top plan view of FIG. 12;

FIG. 17 is a rear perspective view of FIG. 12; and,

FIG. 18 is a front perspective view of FIG. 12.
